UNITED STATES PATENT OFFICE.

FRANK A. BROWNELL, OF ROCHESTER, NEW YORK.

ARCH SUPPORT.

Application filed June 20, 1923. Serial No. 646,502.

My present invention relates to shoes and more particularly to devices built in or insertable into shoes to give support to weak or fallen arches and the invention has for its object to provide a simple, compact and durable device of this nature that can be conveniently and accurately adjusted to a raised or lowered position which gives the desired support to the foot of a particular wearer. To these and other ends the invention resides in certain improvements and combinations of parts all as will be herein-after more fully described, the novel features being pointed out in the claims at the end of the specification.

In the drawings:

Figure 1 is a fragmentary longitudinal section through a shoe provided with an arch support constructed in accordance with and illustrating one embodiment of my invention.

Figure 2 is a side view of the arch supporting device removed from the shoe.

Figure 3 is an enlarged longitudinal section through the arch supporting device in normal or lowered position.

Figure 4 is a similar view of the arch supporting device partly broken away with the parts in a raised position.

Figure 5 is an enlarged perspective view of the casing member.

Figure 6 is an enlarged perspective view of the shank member partly broken away.

Figure 7 is a plan view of the arch supporting device removed.

Figure 8 is a bottom view thereof.

Figure 9 is an enlarged plan view of the cam mechanism in one position of adjustment.

Figure 10 is a similar view of the cam mechanism in another position of adjustment.

Figure 11 is an enlarged transverse section on the line 11-11 of Figure 8.

Similar reference numerals throughout the several views indicate the same parts.

My invention is applicable both to arch supporting devices insertable in shoes as an accessory and to devices that are built into the shoe but in the present instance I have illustrated the latter arrangement. Referring more particularly to the drawings 1 indicates a shoe having a heel 2, an outsole 3, an insole 4, and a sock lining 5. The arch supporting mechanism is preferably located

on the insole 4 beneath the sock lining 5 and accessible for adjustment from the exterior of the shoe through an opening 6 in the outsole 3. It embodies a metal shank stiffener 7 having an aperture 8 in the rear end thereof by means of which it is secured to the heel portion of the shoe with a nail 9. Forwardly of this opening the shank stiffener is provided with a bearing opening 10 and with short longitudinal slots 11 adjacent thereto. Fitted against its under side is a shallow casing member 12 having lugs 13 occupying the slots 11 to guide the casing for longitudinal movement. The bottom wall of the casing is also provided with longitudinally elongated openings 14 and 15.

Overlying the shank stiffener 7 is a spring metal arch supporting plate 16 the forward end of which is secured to the insole 4 by nails 17 passing through openings 18. The rear end is provided with openings in which are riveted reduced portions 19 on the lugs 13 of the casing 12 so that the rear end of the arch supporting plate moves with the casing 12 in the guide slots 11 and the casing 12 is held against the shank stiffener 7 and extending through the slot 15 of the casing.

Rotatably mounted within the bearing opening 10 is a disk 21 having a cam slot 22 therein and a non-circular central opening 23 to receive an operating key or tool inserted through the opening 6 in the outsole with which the opening 23 is in alignment. Passing through the cam slot 22 and slidably occupying the same is the enlarged central portion of a rivet 24 having its upper ends secured in the arch plate 16 at 25 and its lower ends secured in the casing 12 at 26.

The forward end of the shank stiffener 7 is provided with an opening 26^a while the arch plate 16 is provided with an adjacent opening 27. A tongue 28 on the shank stiffener 7 and a tongue 29 on the plate 16 interlock with each other through these openings and prevent forward movement of the arch plate at this point.

The operation of the device will be apparent from the foregoing description. A suitable key (not shown) is inserted through the aperture 6 in the bottom of the shoe and through the elongated slot 14 into the opening 23 in the cam 21. Rotation of the cam in its bearing 10 in the shank stiffener 7 car-

ries the rivet 24 back and forth longitudinally of the shank and with it the casing 12 and the rear end of the arch plate 16. When the pin 24 is in the extreme rearward position of Figures 3 and 9 the arch plate 16 is flattened out against the shank stiffener 7 but when it occupies the forward position of Figures 4 and 10 it draws together the ends of the arch plate and causes it to bulge or bow upwardly and give the degree of curvature desired to properly support the foot. As before stated, these sliding movements are guided both by the lugs 13 on the casing 12 travelling in the slots 11 in the shank stiffener 7 and by the headed pin 20 secured in the shank stiffener and passing through the casing.

I claim as my invention:

1. In an adjustable arch supporter for shoes, the combination with a shank stiffener having a bearing opening therein and a resiliently flexible arch plate carried thereby having one end fixed against longitudinal movement, of a cam disk turning in the bearing and an operating connection for the arch plate engaging the cam disk inwardly of its periphery whereby to operate the other end of the arch plate in longitudinal directions.

2. In an adjustable arch supporter for shoes, the combination with a shank stiffener and a resiliently flexible arch plate superposed thereon having one end fixed against longitudinal movement, of a rotatable member on the shank stiffener having a cam slot therein and a pin on the arch plate cooperating with the slot to flex the plate into a bowed position when the rotatable member is turned.

3. In an adjustable arch supporter for shoes, the combination with a shank stiffener having a bearing opening therein and a resiliently flexible arch plate superposed thereon, of a rotatable disk in the bearing opening having a cam slot therein and a pin near one end of the arch plate cooperating with the slot, the opposite end of the arch plate being fixed to the shank stiffener against longitudinal movement.

4. In an adjustable arch supporter for shoes, the combination with a shank stiffener and a resiliently flexible arch plate superposed thereon having one end fixed against longitudinal movement, of a rotary element on the shank stiffener adapted to draw together the ends of the arch plate to regulate its curvature, and a housing member for the rotary element located on the under side of

the shank stiffener and movable with the arch plate.

5. In an adjustable arch supporter for shoes, the combination with a shank stiffener and a resiliently flexible arch plate superposed thereon and having one end fixed against longitudinal movement, of a rotary member carried by the shank stiffener and having a cam slot therein, a housing for the rotary member guided for longitudinal movement on the under side of the shank stiffener and a pin connecting the other end of the arch plate and the housing for joint movement, said pin extending through the cam slot.

6. In an adjustable arch supporter for shoes, the combination with a shank stiffener having a bearing opening therein and a resiliently flexible arch plate superposed thereon and having one end fixed against longitudinal movement, of a rotary cam disk arranged in the bearing opening, a slidable member on the under side of the shank stiffener and means connecting the free end of the latter with the sliding member and arranged to be actuated by the cam.

7. In an adjustable arch supporter for shoes, the combination with a shank stiffener having a bearing opening therein and a resiliently flexible arch plate superposed thereon and having one end fixed against longitudinal movement, of a rotary cam disk arranged in the bearing opening, a housing for the disk arranged on the under side of the shank stiffener and guided therein and a pin connecting the housing with the free end of the arch supporting plate and adapted to be acted upon by the cam to force the ends of the arch supporting plate together.

8. The combination with a shoe having an outsole provided with an opening, of a shank stiffener within the shoe, a resiliently flexible arch plate superposed thereon and having one end fixed against longitudinal movement, a key controlled element rotatably disposed within an opening of the shank stiffener to act upon the arch plate and move its free end toward its fixed end, said rotary element being provided with an opening in alignment with the opening in the outsole and accessible therethrough by means of a key and a guide movable upon the shank stiffener and having an opening in registry with the opening of the rotary element.

FRANK A. BROWNELL.
